UNITED STATES PATENT OFFICE

ZUZA WALOVICH, OF HAWLEYVILLE, CONNECTICUT.

DESIGN FOR A SLAVONIAN-PEASANT DOLL.

47,513.

Specification for Design. Patented June 22, 1915.

Application filed March 30, 1915. Serial No. 18,196. Term of patent 7 years.

To all whom it may concern:

Be it known that I, ZUZA WALOVICH, a citizen of the United States of America, residing at Hawleyville, in the county of Fairfield and State of Connecticut, have invented a new, original, and ornamental Design for a Slavonian-Peasant Doll, of which the following is a specification, reference being had to the accompanying drawing, forming part thereof.

In the drawings, Figures 1 and 2 are front and rear elevational views, respectively, of a Slavonian peasant doll, showing my new design.

I claim:—

The ornamental design for a Slavonian peasant doll, as shown.

ZUZA WALOVICH.
